US00D341615S

United States Patent [19]

Ifejika

[11] Patent Number: Des. 341,615

[45] Date of Patent: ** Nov. 23, 1993

[54] DEVICE FOR CLEANING CONTACT
LENSES

4,807,750 2/1989 Ryder 134/901
4,852,594 8/1989 Chen 134/901

[75] Inventor: Victor A. Ifejika, London, England

Primary Examiner—Bernard Ansher

[73] Assignee: CCL (Vision) Limited, London,
England

Assistant Examiner—R. Barkai

Attorney, Agent, or Firm—Iandiorio & Dingman

[**] Term: 14 Years

[57] CLAIM

[21] Appl. No.: 538,168

The ornamental design for the device for cleaning
contact lenses, as shown and described.

[22] Filed: Jun. 14, 1990

DESCRIPTION

[30] Foreign Application Priority Data

Dec. 15, 1989 [GB] United Kingdom 2003357
[52] U.S. Cl. D16/124
[58] Field of Search D16/124; D24/218;
134/901; 206/5.1
